DESIGN FOR A SHOE

Ben Solnit, Los Angeles, Calif.

Application May 11, 1938, Serial No. 77,110

Term of patent 3½ years

To all whom it may concern:

Be it known that I, Ben Solnit, a citizen of the United States and residing in city of Los Angeles, county of Los Angeles, State of California, have invented a new, original, and ornamental Design for a Shoe, of which the following is a specification, reference being had to the accompanying drawing, forming part thereof.

Fig. 1 is a front perspective view of a shoe showing my new design.

Fig. 2 is a plan view thereof.

The ornamental lacing is applied to the shoe by threading leather stripping through the upper and tongue through holes punctured in the outer covering. The inner lining is unpunctured.

I claim:

The ornamental design for a shoe, substantially as shown and described.

BEN SOLNIT.
